(57) **CLAIM**

The ornamental design for an antenna for small electronic devices, as shown and described.

DESCRIPTION

FIG. 1 is a front-left side top perspective view of an antenna for small electronic devices showing our new design;

FIG. 2 is a front view of the antenna of FIG. 1;

FIG. 3 is a rear view of the antenna of FIG. 1;

FIG. 4 is a left side view of the antenna of FIG. 1;

FIG. 5 is a right side view of the antenna of FIG. 1;

FIG. 6 is a top view of the antenna of FIG. 1; and,

FIG. 7 is a bottom view of the antenna of FIG. 1.

The broken lines in the figures depict environment that forms no part of the claimed design.

1 Claim, 3 Drawing Sheets
